CLAIM

The ornamental design for a panel for use in forming an elevated platform, as shown and described.

DESCRIPTION

FIG. 1 is an upper front perspective view of the claimed design;

FIG. 2 is an upper rear perspective view of the claimed design;

FIG. 3 is a first lower perspective view of the claimed design;

FIG. 4 is a second lower perspective view of the claimed design;

FIG. 5 is a third lower perspective view of the claimed design;

FIG. 6 is an upper plan view of the claimed design;

FIG. 7 is a lower plan view of the claimed design;

FIG. 8 is a side view of the claimed design;

FIG. 9 is an end-on view of the rear of the claimed design, shown in larger scale; and,

FIG. 10 is an end-on view of the front of the claimed design. The panel for use in forming an elevated platform is shown with symbolic breaks in its length and width. The appearance of any portion of the article between the break lines forms no part of the claimed design.

The broken lines shown in the figures are for the purpose of illustrating portions of the panel for use in forming an elevated platform, and form no part of the claimed design.
